UNITED STATES PATENT OFFICE.

HENRY HIGGIN AND JOSEPH HAAS, OF NEWPORT, KENTUCKY, ASSIGNEES TO THE
HIGGIN MANUFACTURING COMPANY, OF NEWPORT, KENTUCKY, A CORPORATION
OF WEST VIRGINIA.

WINDOW-SCREEN.

1,273,222.

Specification of Letters Patent. Patented July 23, 1918.

Application filed April 27, 1917. Serial No. 164,852.

To all whom it may concern:

Be it known that we, HENRY HIGGIN and JOSEPH HAAS, citizens of the United States, and residents of Newport, in the county of Campbell and State of Kentucky, have invented certain new and useful Improvements in Window-Screens, of which the following is a full, clear, and exact description, reference being had to the accompanying drawings, making part of this specification.

Our invention relates to window screens, particularly those which are pivotally hinged so as to swing open away from the window frames in which they are mounted. It is our object in screens of this character to provide for a simple and effective means for obtaining such a pin mounting, wherein particularly the one pin is adapted to be pulled inwardly by an easy operation. We also desire to provide a simple and easily operated catch pin for the holding of this form of screen to the window frame.

In wide screens where the tension on the wire netting is liable to draw the frame out of square, braces of various kinds have been used. These have all had to be fastened to the frame with screws, rivets, clenches or solder, which consumes time, and when finished mars the appearance of the light metal frame screen.

It is our desire in this invention to cut the brace to a correct length, so that the ends of the brace will butt against the inner edges of the screen frame. The brace is then located on the wire netting by creasing the netting with a proper tool to receive a round rod, and placing the rod in the groove. A U-shaped molding is then clamped on, almost enveloping the rod and binding the wire netting firmly between the two parts. The wire netting is then attached to the frame in the usual manner for this type of screen.

The combined strength of the wire netting thus confined, together with the brace and the close endwise fit of the brace, makes this method of bracing valuable for metal screen work.

In the retaining of the wire in the frames, so as to be removable, splines are dropped into channels of the frame pieces, so as to confine the wire therein. To improve over past structures, this spline and the channel walls are made with no substantial spring to them and a pin is driven in behind a

small channel shoulder to lock the connection.

In the corner pieces of the molding of the new screen of this invention, we provide for a great simplification of the structures of the past and also provide a corner brace which allows of a pin, such as is used in hanging the screens of this invention, to pass through them without any necessity of drilling out the corner pieces.

The above objects and advantages we accomplish by that certain construction and arrangement of parts to be hereinafter more specifically pointed out and claimed.

In the drawings,

Figure 1 is a front elevation of the screen.

Fig. 2 is a detail elevation of the corner piece and means for retaining the slidable hinge pin.

Fig. 3 is a vertical section of the screen frame showing the corner pieces and the hinge pin.

Fig. 4 is a detail perspective view of one of the halves of a corner piece.

Fig. 5 is a rear plan view of the exterior plate of the sliding pin device.

Fig. 6 is a side elevation of the corner brace.

Fig. 7 is a front elevational detail of the corner of the screen showing the sliding pin device.

Fig. 8 is a detail elevation of a screen reinforced by the new reinforcing means.

Fig. 9 is a perspective detail of this reinforcing device.

Fig. 10 is a section through the screen frame showing the lower spring pin catch.

Fig. 11 is a detail elevation of the pin or plunger of this catch.

Fig. 12 is a side elevation of the screen showing the manner of hanging the same.

The screen molding 1, which forms no part of the novelty of our invention herein, comprises a single sheet of metal bent around to form a rectangular hollow frame and a channel on the inner edge thereof for removably mounting screen wire 2, by means of a spline or bar 3. The screen corner braces are made up of two pieces of metal which may or may not be welded together. The two pieces are alike and are assembled back to back to form the corner braces.

These pieces have a depressed portion 4 along their median line from which the walls of the depression are curved out and

then bent sharply over at 5, so as to form a partly closed passage 6 along the edges of the brace. The bending of the metal in this manner provides a very stiff brace, and 5 yet there are but two pieces of metal, which are easily stamped and do not even require welding in most instances. If they are welded, there will be several spot welds 7 along the meeting line of the two pieces.

10 The corners of the bends or flanges 5 are cut out at 8 so as not to interfere with the support of a hinge pin in the passage 6, and to permit the pins to extend out from the passages. The pins may be welded in 15 the passages for one side of the screens without preventing a mounting and withdrawal of the screens from their hinged mounting.

It can be seen that the corner braces above described thus are not only an extremely 20 simple and strong corner brace which is readily formed up out of sheet metal, but also that they adapt themselves to hinge pin supported screens.

In mounting the hinge pins in the screens, 25 the fixed pin 10 may, as stated, be welded in place in the passage along the edge of one of the corner braces. This brace is put into the screen in the ordinary manner at one of the upper corners thereof, and the 30 screen molding provided with an aperture to permit the passage of the pin.

The movable pin 11 is of considerable length and has tightly secured to it a small plate 12, which has a screw hole 13 therein. 35 The pin is inserted in the molding of the screen with the plate end of the pin extending into the rectangular portion of the molding. The molding has a small slot 14 therein located adjacent the position which 40 the plate will take, and set over this slot is a small plate 15. This cover plate 15 forms a cover for the slot and in its rear face has a knob or lug 17 projecting inwardly. A screw 16 is passed through the hole 16^a in 45 the cover plate 15 and takes into the threaded opening 13 in the plate 12. The slot 14 in the molding is long enough to allow the lug 17 to engage in one end of the slot when the cover plate is in parallel position with 50 the molding strip. It will be obvious from this construction that by loosening the screw 16 the lug 17 on the cover plate can be lifted from the slot 14 and the cover plate turned around and the plate 15 pushed to 55 shift the screw 16 to the other end of the slot, and then the lug 17 when the screw is tightened will also engage in the slot.

To assemble the construction, the two 60 members of the corner brace are placed together and the pin 11 with its plate 12 located in the open space of the brace with the pin projecting through the opening 8.

These assembled parts are then inserted together, with the respective legs of the brace 65 in the two molding strips that are to form

a corner, an aperture being provided at the end of the molding to allow for the passage of the pin. The parts are so proportioned that when the small exterior plate is set with its screw supporting end away 70 from the protruding end of the pin, and with the screw in engagement with the pin plate, then the protruding end of the pin will be about flush with the side molding of the screen.

75 If the exterior plate is set lengthwise with the molding slot and the screw fastened in, the knob on the plate will engage the other end of the slot and hold the device tightly locked against movement. To extend the 80 pin the screw is loosened and the small plate pushed along to carry the screw toward the protruding end of the pin, the screw moving in the slot. This will move out the pin, and the plate may be swung around and 85 locked in position as before except that it is reversed in position.

The screen may, as is obvious, be mounted by the above means in any desired journals at the upper corners of the window 90 frame, and the screen thereby hinged so as to swing out from the window sill, as desired. A screw, a pin, two small plates of simple construction, a slot in the molding and the labor of welding the one plate to 95 the pin, make up the entire device.

At the base of the screen molding it is desirable to have some sort of catch to prevent the screen from being opened out from the outside by unauthorized persons. For 100 this purpose, a piece of sheet metal is provided, which is bent around at one end to form a hollow plunger 20. The plate is then extended as a flat bar 21. The molding of the screen has a round aperture at 105 the base to permit of insertion of the plunger from below, and the walls of the molding above are slotted to permit of the passage of the flat bar portion.

A spring is placed in the hollow of the 110 plunger portion and the device thrust up in the base molding until the bar portion protrudes above. A ring 22 is provided over which the bar is bent at 23, which holds the plunger from removal and provides a 115 finger hold. The spring tends to force the plunger down, so that it will form a spring latch, in connection with any desired socket member mounted on the frame of the window.

120 As above stated, one of the objects of this invention is to provide a brace for the wire mesh in screens where there is any long stretch of wire. The device for reinforcing extra length wire netting in screens 125 in the past has been to build, on the main frame of the screens, the desired number of cross frame portions. These have not been mounted on the wire and have had to be large and thus unsightly, and have cost 130

considerable to build and put into the screens. In a hinged screen such as has been above described, or in swinging doors and the like, there is a strong tendency of 5 the screens to pull out of shape unless there is some reinforcement.

In our new bracing device, a round bar 30 of suitable metal is provided which is of the exact size to fit snugly between the 10 inside edges of the frame where it is to be mounted. The wire is creased and the bar set in the crease, taking up in a usual case say one inch of the wire netting. The netting is pressed over the bar and held 15 confined in this position by the metal strip 31 which is bent around the bar over the wire.

A piece of netting so reinforced may then be set in a rewirable screen frame, as shown 20 in the drawings, with no difficulty. The economy of the structure and its mounting seem apparent over prior devices. If proper care is taken, the ends of the bar and of the confining strip as well will abut the 25 inner sides of the frame pieces or moldings of the screen, and will hold stiffly in place

when the netting is tightly drawn. There will, under proper conditions, be no tendency to tilt or pull out of position 30 the reinforcing piece, but if there should, a drop of solder would make it absolutely rigid. The device will give a stiffness and strength to the netting along the line of reinforcement, and brace the screen in all 35 its parts thoroughly. So far as we are aware, no one in the past has devised a reinforcing member for screen netting which is secured to the netting itself, and accordingly we feel that the failure to mention 40 the various other means in which this could be accomplished should not be construed as a limitation of our claims for novelty on this feature.

As stated above, the splines which secure 45 the wire removably in the screen are made to fit into the channel of the screen moldings. It will be noted that the channel portions of the moldings have small beads 32 formed along their outer walls by a slight 50 return bend of the metal from which they are constructed. The splines are shaped so that they present a flat wall 33 to the inner channel walls and a slight longitudinal depression 34 to the beaded edge 55 of the outer wall. The edges of the splines abut the bases of the channels.

It is desirable in the rewirable metal screen frame, that the resiliency of the metal either of the channel or the splines, 60 should not be counted upon for the holding of the wire netting in place throughout the life of the screen. Thus the channel portions of the moldings and the splines in this construction are neither of them 65 resilient in any appreciable manner.

The splines can be tipped into the grooves because of the clearance allowed by the depressions 34, but as is noted this depression leaves some clearance space between it and the beaded edges of the channel walls, after 70 the splines are in place. While the splines might remain in place for a long time without any other devices for holding them in, we have found that it is desirable to provide a lock or seal to hold them in. As a 75 preferred form of such a member, we provide small pins 35 which are forced into the place between the depressions of the splines and the beads on the outer channel walls. These pins act to wedge or lock 80 the splines in place until the pins are removed, force the inner walls of the splines firmly up against the inner channel walls, and generally make a good tight fit for the splines and prevent their jarring loose. 85 After rewiring the screens, the splines will not always remain true to line, and the pins will keep them flat and smooth in the channels, making a much neater job than is possible in the other rewirable screens of 90 the day.

It is believed that in the above matter the operation of the parts where not obvious has been explained and the advantages resulting from their construction and use 95 pointed out, so that it is not believed necessary to deal with them any further.

This spring pin latch is also of very simple construction, as it is made up of a single piece of metal, a ring and a small 100 spring.

Having thus described our invention, what we claim as new and desire to secure by Letters Patent, is:-

1. In a screen adapted for hinging in 105 suitable journals, a hollow frame for the screen, a pin hinge sliding in the frame, means on the pin adapted to be engaged by a screw or its equivalent, and an adjustable member on the frame carrying such screw, 110 for the purpose described.

2. In a screen, a hollow frame, a sliding hinge pin therein, said frame provided with a slot, a cover plate for said slot, means on the plate for engaging the pin, said plate 115 adapted to be shifted for changing the position of the pin, for the purpose described.

3. In a screen, a hollow frame member, a hinge pin therein and extending therefrom, a plate secured to the pin, said frame provided with a slot, a cover plate adjustable over said slot, and means thereon for engaging the plate on the pin whereby the adjustment of the cover plate will shift said hinge pin. 120

4. In a screen, a hollow frame member, provided with a slot therein, a cover plate having a lug on one end to engage the walls of the slot, and a screw on the other end passing through said slot, a sliding hinge 130

- pin, and means on the hinge pin for engaging the screw whereby the reversing of the position of the plate will work a longitudinal movement of the pin.
5. In a screen, hollow frame members adapted to be set against each other to form a rectangular structure, and corner reinforcements for said frame comprising plates of angle form, having longitudinal depressions and set together with the depressed portions against each other, so that the walls of said depressions flare away.
6. In a screen, hollow frame members adapted to be set against each other to form 15 a rectangular structure, and corner reinforcements for said frame comprising plates of angle form, having longitudinal depressions and set together with the depressed portions against each other, so that the walls 20 of said depressions flare away, the outer walls having a return bend from said depressed portions thereby forming a hollow passageway for a hinge pin or the like.
7. In a screen, hollow frame members 25 set together to form a rectangular frame, and corner reinforcements for said frame comprising two angle-shaped pieces of metal having depressions along the median line, and flaring walls therefrom, said pieces set 30 with the depressed portions abutting each other, for the purpose described.
8. In a screen, a hollow frame, a sliding pin therein, and corner braces for said hollow frame, said braces being formed of 35 metal pieces so shaped and set together as to leave a passageway for the pin inside of the said brace.
9. In a screen, the combination with a hollow frame and a sliding pin to slide 40 therein, a corner brace for said frame, said brace being expanded at its outer edge to form a passageway for the retention of the pin.
10. A wire screen comprising a framework, with a unitary piece of wire mesh 45 mounted therein, said wire mesh provided with a reinforcing member extending across the width of the wire, with means for securing the wire thereto, said reinforcing member being of a length to fit snugly between the sides of the frame without attachment to the frame.
11. A wire screen comprising a framework, with a unitary piece of wire mesh mounted therein, said wire mesh provided 50 with a rod extending across the width of the wire, with a metal strip bent around the wire to secure the same to the rod, said rod being of a length to fit snugly between the sides of the frame.
12. In a window screen, the combination 55 of metal molding for the frame therefor, said moldings being formed with substantially non-resilient channels for receiving the gauze, substantially non-resilient wire 60 retaining splines adapted to fit closely in the channels, and small pins set into the channels longitudinally to lock the splines in place.
13. In a window screen, the combination 65 of metal molding for the frame therefor, said moldings being formed with substantially non-resilient channels for receiving the gauze, having a bead on the one upper edge thereof, substantially non-resilient wire 70 retaining splines adapted to fit closely in the channels, and small pins set into the channels between the splines and the beads longitudinally to lock the splines in place.

HENRY HIGGIN.
JOSEPH HAAS.
